MATCH SPLINT FORMING MACHINE

Rudolph F. Onsrud and Oscar Onsrud, Chicago,
Ill., assignors to Onsrud Machine Works, Inc.,
Chicago, Ill., a corporation of Illinois

Application March 20, 1936, Serial No. 69,910

3 Claims. (Cl. 144—41)

This invention relates to machines for use in the manufacture of matches and the construction disclosed herein is designed particularly for forming match splints from wood. The purpose of 5 the invention is mainly to produce uniformly perfect splints at a comparatively high rate and to avoid some of the objections to prior methods of making match splints preparatory to treatment and heading and packaging of the splints. 10 Other objects of the invention are to improve the general arrangement of a molding machine suitable for the specific class of work mentioned, and to improve details of construction thereof enabling continuous and reliable operation of 15 the machine; and the provision of various conveniences in the matter of accessibility to the operating parts and instant spacing apart as a unit of such elements of the machine as are near the line of travel of material operated upon 20 so that access may be had to the material in any stage of the operation.

The objects of the invention are accomplished by means of the construction illustrated in the drawings, wherein—

25 Figure 1 is a perspective view of the improved match splint molding machine.

Fig. 2 is a fragmentary longitudinal section through the center of the machine, as indicated by the line 2—2 on Fig. 4.

30 Fig. 3 is a sectional view taken horizontally through the machine as indicated by the line 3—3 on Fig. 2.

Fig. 4 shows the machine in end elevation and partly broken away and partly in section as indicated by the line 4—4 on Fig. 2.

Fig. 5 is a fragmentary sectional detail as indicated by the line 5—5 on Fig. 3.

Fig. 6 is a fragmentary sectional view as indicated by the line 6—6 on Fig. 3.

40 Fig. 7 is a sectional view taken on line 7—7 of Fig. 3, showing in detail adjusting means for a lower grooved guide plate at the splint delivery end of the machine.

Fig. 8 is an enlarged sectional view showing 45 a fragment of one of the cutters and indicating in cross section the form of the product produced thereby.

In the production of match splints from wood it is important that the intended cross section 50 of the splint is maintained from end to end thereof without any variation such as a bar or recess at the end of the splint which would result in non-uniformity in the shapes of the heads of the matches or unequal adherence of the friction responsive elements of the head. Hereto-

fore the highest grade match splints have been made by splitting blocks of clear wood, such as white pine. Long splints have also been made by the use of molding machines. Then the splints are cut across grain into the desired 5 match lengths. The ends, however, at the cross cuts are not exactly even and uniform.

To enable the successful use of a comparatively cheap wood but of the highest quality for the purpose, such as aspen, the present machine is designed to use such parts of aspen wood as are free from knots in the form of small clear cards which are in the grain direction, of the length of the required finished splint, and which this machine cuts in that direction into the desired cross sectional form. The cards are stacked and placed in a chute at one end of the machine from which they are taken one by one, by a continuous feed mechanism, and caused to travel between upper and lower molding cutters and 20 then delivered to a belt in perfect form, which carries the splints on for the finishing chemical treatment, partial drying, and heading.

Each of these machines, when arranged to operate upon cards four inches in width, produces 25 twenty-seven splints from each card and at the rate of four and one-half million splints in ten hours:

The main features of construction of the machine are a frame upon which is mounted for 30 vertical motion a table which carries feed mechanism for moving the cards horizontally along the table and also carries the lower molding cutter, while in relatively fixed position on the main frame above this table is the upper molding cutter, upper feed belt, and pressure shoes for holding the stock while it is being cut.

With this arrangement of molding machine the guide table, lower feed mechanism and lower cutter may be instantly shifted downwardly clear 40 of the upper cooperating units, and thus afford access to the work in any stage of operation, allowing for prompt clearance of the machine if necessary and access to the cutting units, each of which is also shiftable horizontally away from the operating position.

In the drawings the main machine frame is indicated at 1. The table 2 which supports the cards during the cutting operation is rigid with a vertically movable frame 3 arranged to travel 50 along guide flanges 4 on the main frame 1. The table 2 and frame 3 are normally held in the exact upper working position by the toggle mechanism 5 shown in Fig. 4. This mechanism comprises a turn buckle form of links 6 pivoted at 55

their upper ends at 7 to frame 3, and at their lower ends at 8 to arms 9, fast on rocker shaft 10. By drawing the handle 11, Fig. 1, forwardly and downwardly the table 2, frame 3 and the mechanisms carried thereby are lowered as shown in this figure away from the upper cutter 12, and the upper guide and pressure shoes 13, 14 and 15, and an upper feed belt 16, Fig. 2. The lower feed belt 17 moves down with the table 2.

10 Power for driving the feed belts is derived from motor 18 and power for the upper cutter 12 is supplied by motor 19, Fig. 3, while the lower cutter 20 is driven by motor 21.

The motor 18, Fig. 5, through the belts 22 and speed changing tapered pulleys 23 and 24, drives the vertical shaft 25 upon which is gear 26. Gear 26 meshes with gears 27 and 28 for respectively transmitting motion to the feed belts 16 and 17.

The gearing for upper feed belt drive shaft 29 is indicated in Fig. 3, and consists of worm 30, worm-wheel 31 and chain drive 32, which operates shaft 28 through clutch 33. This clutch may throw out against the action of spring 34 in case of an overload on shaft 29.

25 The lower feed belt 17 is driven by similar means as illustrated in Fig. 5. Gear 28 is fast to a vertical shaft 35 to which is splined so that it may slide vertically thereon, a worm 36 which meshes with worm wheel 37 on the horizontal shaft 38. This shaft carries the drive sprockets 39 for belt 17, Fig. 2.

When the table 2 and its supporting frame 3 are lowered away from the upper cutter 12, upper feed belt and pressure feet, the lower feed belt unit moves down with the table 2 to which it is secured, and the worm wheel 36, Fig. 5, slides down along shaft 35.

The support 40, Fig. 2, which carries and houses the upper feed belt, also supports motor 18 and the transmission gearing therefor. This unit may be adjusted vertically as the frame 40, Fig. 5, is guided in vertical ways 41 on the main frame 1. Vertical adjustment is effected by handwheel 42. The belt pressure is further regulated by adjustment of the resilient pressure plate 43 through screws 44. The belt is tightened by rotating eccentric shaft 45. The upper belt feeds the wooden cards operated upon by frictional engagement with the tops of the cards and the lower belt feeds the cards one at a time, by engagement with the rear edges thereof, by means of the lugs 46 secured to the links of the belt.

These lugs are of tooth form and pass through guide slots 47 at the end of table 2. The cards are pushed forward along the table between it and the stationary guide 48 and from this position each card is pushed by the following one into position to be carried forward along the table by means of belt 16. The pressure foot 15 is beveled at its end 49 so as to guide the card down firmly against the table top. Springs 50 exert sufficient pressure against foot 15 to firmly hold the card during operation of the lower cutter 20 which rotates against the direction of travel of the card and grooves it to form half way through. The cuts are completed from the upper side by cutter 12, which also rotates against the direction of movement of the cards and the latter are held against the table top, while the upper cutter 70 operates thereon, by the resilient pressure feet 14 and 13. The latter is longitudinally grooved so as to receive in separate channels the splints, as formed.

The compression of the springs 50 for the pressure shoes is regulated by screws 51 and the whole

unit may be raised or lowered along guides 52 in frame 1 by the hand wheel 53. This pressure shoe unit also carries the outlet conduit 54 for the material which is cut away by the upper cutter 12. This conduit is connected with suction 5 means for drawing a blast of air upwardly there-through. Material which is removed by the lower cutter 20 is carried out of the machine through the exhaust outlet 55.

The grooved shoe 13 is above a similarly 10 grooved plate 56 in the table 2 and the latter is adjustable in all directions as illustrated in Figure 7. The wedge 57, operated by screw 58, serves to shift this plate up or down in exact parallelism with grooved shoe 13. It is necessary to 15 have the end of the plate quite close to cutter 20, and it is copper tipped at 59 to guard against the cutter 20 engaging a hard metal in case of 20 improper adjustment of the plate.

The wooden cards which are operated upon are 20 indicated in a vertical column at 60, Fig. 2. They are fed downwardly by the weight 61 which carries a pivoted tooth 62 projecting into the magazine chute 63 through slot 64 therein. Stacks of 25 cards are fed to the top of the chute above the tooth 62 and the latter may swing downward around its pivot against the action of spring 65 whenever the weight is lifted by means of cord 66. At that time the tooth ratchets up over the 30 cards.

The cutting motors 19 and 21 are controlled by switches 67 and 68 and the feed mechanism motor 18 is controlled by switches 69. Relays for these switches and other electric control devices for the motors are located in box 70 mounted on the back of frame 1, and on the base 72 of the 35 machine as appears in Fig. 1.

The feed belts may be turned by hand independently of motor 18 by means of the wheel 73, Fig. 5, which is attached to pulley 24.

40 The belt 17 may be adjusted forwardly or backwardly independent of belt 16 by releasing clutch 74, Fig. 4, which is similar to clutch 33 previously described, and ordinarily serves the same purpose of disengaging in case of an overload on the lower belt feed. In this case the clutch is partly enclosed by the gear housing and is accessible by removing the cover 75 attached to the housing.

The teeth 46 carried by the lower feed belt 50 pass through slots in the feed belt guiding and guarding structure 71, Fig. 2.

The upper and lower cutting units are similar in construction and mounting, except that the lower cutting unit is carried by the vertically adjustable frame structure 3, whereas the upper cutting unit is mounted upon frame 1, but each is independently adjustable vertically as in guideways 76, Fig. 1, and by hand wheels 78. The cutting units are also movable in the horizontal 60 guideways 79 sidewise of the machine toward and away from the working position by means of hand levers 80 pivoted at 81 and having a link connection 82 to the motor frame. Gauges 83 and 84, Fig. 4, when in contact determine the 65 working position of the tool.

A slight vertical tilting adjustment of the cutting motor units is also desirable and is effected by the screws 85 and 86.

In the operation of the machine the feed chute 63 receives a continuous supply of the wooden cards 60 and the weight 61 is lifted from time to time to maintain a downward pressure on the cards at the lower end of the stack. The lowermost card can tilt downward over the tooth 46 75

passing beneath it and into position to be engaged by the next oncoming tooth which serves to push the card along the table 2 and beneath the fixed guide 48. The following cards push the foremost one into position to be engaged by feed belt 16 and the cards are by this belt forced one after another into the space between the cutter 20 and the pressure feet 14 and 15. The cards are first grooved smooth underneath by cutter 20 and then above by cutter 12, and while the cut is being finished by cutter 12 the splints pass into and between the grooves formed in pressure foot 13 and in plate 56, and are pushed out of the machine by the oncoming product, and delivered to a belt which carries the splints along for treatment and completion into matches.

The operation is rapid and simple and the machine is pleasing to work, for in case of difficulty because of inferior stock the cooperating units 20 of the machine may be quickly and widely separated by drawing the handle 11 forwardly, thus enabling easy clearing of the machine and the restoring of the movable unit to the exact operating position.

25 Close adjustments of the various operating parts of the machine are possible and important; for instance it is found that the upper feed belt 16 should be very slightly inclined with reference to the table top 2 so as exert more pressure on the top of the cards when first engaged by the belt than when leaving the belt. There is space between the cards only at the time of leaving the magazine and when first engaged by the upper feed belt. After that the cards come together and 35 the operation is continuous, as though on a continuous strip of material.

We claim:

1. In a match splint molding machine a frame structure having mounted thereon an auxiliary frame for vertical movement on said frame structure; said frame structure carrying above said auxiliary frame a supply magazine for material operated upon, a belt conveyor for such material, a pressure foot, a cutter and pressure foot all in 40 succession; said auxiliary frame being equipped with a belt feed for the material operated upon, a cutter, and a grooved plate for receiving material as cut and opposed to one of said pressure feet; a common drive means for both of said belt

conveyors, and a sliding connection between said drive means and the lower belt conveyor arranged to maintain operative relationship between said drive means and the lower belt conveyor irrespective of the vertical movement of said lower frame 5 member.

2. In a match splint molding machine, a main frame structure, an auxiliary frame mounted for vertical movement on the main frame, a supply magazine carried by the main frame and located 10 above the auxiliary frame for material operated upon, an upper belt conveyor for such material, a pressure foot, a cutter and pressure foot all in succession, means for mounting the pressure feet as a unit on the main frame structure for vertical 15 adjustment independently of the main frame structure and the cutter and for vertical movement independently of each other, said auxiliary frame being equipped with a belt feed for the material operated upon, a cutter, a common drive 20 means for both of said belt conveyors, and a sliding connection between said drive means and the lower belt conveyor arranged to maintain operative relationship between said drive means and the lower belt conveyor irrespective of the vertical 25 movement of the auxiliary frame.

3. In a match splint molding machine, a main frame structure, an auxiliary frame mounted for vertical movement on the main frame, a supply magazine carried by the main frame structure 30 and located above the auxiliary frame for material operated upon, an upper belt conveyor for such material, a pressure foot, a cutter and pressure foot all in succession, said auxiliary frame being equipped with a lower belt feed for the material operated upon, a cutter, a common drive 35 means for both of said belt conveyors, a sliding connection between said drive means and the lower belt conveyor arranged to maintain operative relationship between said drive means and the lower belt conveyor irrespective of the vertical 40 movement of said auxiliary frame, a support for the upper belt conveyor and said common drive means mounted on the main frame structure for vertical movement independently of the cutter, 45 a guideway for said support, and means for adjusting the support upwardly and downwardly.

RUDOLPH F. ONSRUD.
